UNITED STATES PATENT OFFICE.

FRANKLIN S. HAY, OF ELTON, WISCONSIN.

WRENCH.

1,135,896.

Specification of Letters Patent. Patented Apr. 13, 1915.

Application filed February 4, 1914. Serial No. 816,411.

To all whom it may concern:

Be it known that I, FRANKLIN S. HAY, a citizen of the United States, residing at Elton, in the county of Langlade and State of Wisconsin, have invented new and useful Improvements in Wrenches, of which the following is a specification.

The present invention relates to improvements in wrenches, the primary object of the same being to provide a movable jaw upon the shank of a stationary jaw which will be automatically forced toward the movable jaw, and the provision of means for sustaining the said sliding jaw against such movement.

The invention further resides in the construction, combination and arrangement of parts set forth in the following specification and falling within the scope of the appended claims.

In the drawings: Figure 1 is a view of a wrench constructed in accordance with the present invention, the movable jaw being retained away from the stationary jaw, Fig. 2 is a central longitudinal sectional view taken through the device as illustrated in Fig. 1, Fig. 3 is a view showing the movable jaw arranged adjacent the stationary jaw for engaging an object between the jaws. Fig. 4 is a plan view looking toward the channeled end of the shank, the movable jaw being in the position illustrated in Figs. 1 and 2. Fig. 5 is a detail horizontal sectional view on the line 5—5 of Fig. 2, Fig. 6 is a detail sectional view on the line 6—6 of Fig. 3, looking in the direction of the handle, Fig. 7 is a detail perspective view of the stationary jaw of the shank with the handle of the movable jaw removed, Fig. 8 is a perspective view of the members forming the handle looking toward the inner end thereof, Fig. 9 is a perspective view of the movable jaw, Fig. 10 is a detail transverse sectional view through the shank 2 showing the cam lock in locking engagement with the shank of the wrench, Fig. 11 is a detail side elevation illustrating the head of the movable jaw provided with a removable tooth block, Fig. 12 is a detail sectional view on the line 12—12 of Fig. 11, and Fig. 13 is a sectional view on the line 13—13 of Fig. 11.

Referring now to the drawings in detail, 55 1 designates the head of the wrench upon which is integrally formed a longitudinally

extending shank 2, which has secured to its end a handle 3, while the numeral 4 designates the movable jaw which is mounted upon the shank 2.

The shank 2 has, what I will term, for the sake of convenience, its front face formed with a centrally arranged longitudinally extending depression or channel 5 which extends from the head of the wrench entirely through the shank. The handle 3 comprises a pair of members, the inner face of each being grooved or recessed to receive the shank, and the inner faces of the said sections of the handle are secured to the shank through the medium of one or more removable members in the nature of screws, indicated by the numeral 6. The walls provided opposite the channel 5 between the head 1 and the handle 3 are formed with teeth 7, the said teeth comprising straight and angular walls, the angular walls inclining toward the head 1 of the wrench.

The movable jaw includes a head 8 which may have attached thereto or integrally formed therewith a carriage which comprises spaced longitudinally extending members 9 and 10 respectively, the member 10 having its inner face formed with teeth 11 which are adapted to co-act with the teeth 7 of the shank, while the numeral 12 designates members connecting the rail ends of the portions 9 and 10. The distance between the longitudinal members 9 and 10 is greater than the width or thickness of the shank 2, so that sufficient play is provided to permit of the teeth of the member 9 being raised from engagement with the teeth 7 of the shank 2, and so permit the free movement of the movable jaw upon the shank of the stationary jaw. The member 10 has its inner end provided with a cam lock 13 which is formed with an offset finger hold or tail 14, whereby the same may be operated by a finger or thumb of a person using the wrench to swing the same into contact with the smooth face of the shank opposite that provided with the channel 5 and with the teeth 7. The member 9, as well as the head 8, is formed with a longitudinally extending depression 15 which is arranged over the channel 5, and secured to the wall providing the said depression and approximately centrally thereof, is a depending removable element 16 to which is secured one of the end convolutions of a helical spring 17. The

spring 17 is of a size to be received snugly within the channel 5 of the shank so as not to extend above the walls provided with the teeth 7, and the head 8 is provided with an opening 18 which registers with the channel 5, and which communicates with a smaller annular opening 19.

Arranged within the opening 19 is a sleeve 22 that has a threaded bore 21, while arranged for rotation in a sleeve disposed opposite the sleeve 22 in the outer face of the opening 19 of the head 1 is a headed threaded member 20. The member 20 engaging the threaded bore 21 of the sleeve 22 serves as an adjusting member for the said sleeve. The sleeve has its inner and closed face provided with an eye 23, whereby the free end of the spring 17 is connected with the sleeve. It will be noted that by rotating the member 20, the sleeve 22 will be brought toward or away from the outer face of the head 1, and as a consequence the tension of the spring 17 will be adjusted.

Arranged within the portion of the channel closed by the handle 3 is a spring arm 24, the same having an enlarged end 25 which is of a thickness equaling the width of the channel, and which is provided with an opening through which the securing element 6 passes, whereby the said spring 24 is retained within the channel 5. The spring arm 24 is provided adjacent its outer end with a stud 26, the said stud passing through an opening 27 in one of the side walls provided by the channel 5 in the shank 2, forward of the handle 3, and the said spring 24 is further provided with a finger 28 which passes through an opening in the side of the shank as well as through a registering opening in one of the members of the handle 3, both the stud 26 and the finger 28 being arranged at a similar angle to and upon the same side of the flat spring member 24. The finger 28 is arranged for convenient operation by the user of the wrench, and it will be noted that a pressure thereon, in the direction of the handle 3, will cause the stud 26 to be retracted within its opening 27 so as not to project beyond the face of the shank. One of the end connecting members 12 is provided with an opening 29 which, when the movable jaw 4 is slid in the direction of the handle, is adapted to receive the stud 26, and so hold the movable jaw 4 against the handle 3 and away from the head 1. A pressure upon the finger 28, however, will retract the stud 26 and permit of the spring 17 drawing the head 4 toward the head 1, and into engaging position with an article arranged between the heads 1 and 8. As has been stated, the distance between the members 9 and 10 is sufficient to permit of the movement of the jaw 4 in either direction upon the shank, so that when an obstacle is engaged between the heads 1 and

8 a pressure upon the shank will cause the carriage of the movable jaw to tilt to bring the same into binding engagement with the shank 2, but in practice I have found it desirable to employ the cam latch or lock 13, 70 as previously described.

The inner front face of the member 9 of the carriage of the movable jaw 4 is beveled or inclined, as indicated by the numeral 30, the said portion 30 extending beyond the members 12, and the handle 3 has one of its ends beveled or inclined, as at 32, the said inclined wall 32 adapted to receive a round wall 31 provided in the lower face of the member 30 to elevate the carriage of the movable jaw and raise the teeth 11 out of engagement with the teeth 7, and also to bring the opening 29 of the member 12 in proper position to receive the stud 26. Also the sides of the handle 3 are formed with depressions 33 so that the members 12 may be received between the inner walls formed by the depressions and the outer sides of the shank 2 when the carriage of the movable jaw is held by the stud 26, while the face of the handle 3 opposite that provided with the inclined corner 32, is recessed, as at 34, to provide for the reception of the cam lock 13 when the movable jaw is locked in its retracted position.

The head 8 of the movable jaw 4 is provided upon its opposite sides, with tongues 50 which are adapted to be received within grooves 51 formed upon the rear recessed face of a block 52. The block has its outer face inclined and toothed, and is provided within one or both of its grooves 51, with a spring strip 52 which is adapted to bear against the tongues 50 to retain the block 52 upon the head 8. The block 52 is employed when the wrench is to be used upon pipes, rods, etc., and, as will be readily noted, is easily and quickly detached from the head 8 when not required for use.

From the above description, taken in connection with the accompanying drawings, the simplicity of the device as well as the advantages thereof will, it is thought, be perfectly apparent to those skilled in the art to which such inventions appertain without further detailed description.

Having thus described the invention, what I claim is:

1. In a wrench, a stationary jaw provided with a channeled shank, the side walls of the channel having their edges formed of transverse teeth, a movable jaw including a head and a carriage arranged upon the shank, said carriage having teeth which contact with the teeth of the shank, a member upon the carriage arranged within the channel, a helical spring connected with the said member, adjustable means arranged upon the head of the stationary jaw and connected with the spring and adapted to regulate

the tension of the spring, a cam lock upon the carriage of the movable jaw adapted to co-act with the stem of the stationary jaw to hold the movable jaw against movement.

- 5 2. A wrench including a head having a shank which is channeled throughout its entire length, the sides provided by the channel being formed with teeth; a handle made up of two sections secured to the shank
10 and closing the channel thereof, a longitudinally disposed spring member having an enlarged end arranged between the opposite walls of the channel and secured thereto, the said member having a finger projecting
15 through an opening in one of the side walls of the channel and one of the members of the handle, said spring being further provided with a stud which extends through an opening in one of the side walls of the channel, a movable jaw including a carriage mounted upon the shank, one of the said members of the carriage having an opening adapted to receive the stud of the spring when the carriage is arranged adjacent the
20 handle, and a spring within the channel and secured between the stationary head and the
25

carriage of the movable jaw for sliding the movable jaw toward the head.

3. A wrench including a stationary jaw having a shank and a handle connected with the shank, the said shank being provided with teeth, a movable jaw upon the shank, said movable jaw including a shank which is provided with teeth which co-act with the teeth of the shank, spring means for sliding the head of the movable jaw toward the head of the stationary jaw, and means arranged within the handle and co-acting with the carriage of the movable jaw for locking the said jaw, and means arranged upon the carriage and co-acting with the handle for elevating the carriage to bring the teeth of the said carriage out of engagement with the teeth of the shank when the carriage is moved into locking position.

In testimony whereof I affix my signature in presence of two witnesses.

FRANKLIN S. HAY.
